UNITED STATES PATENT OFFICE.

MITFORD B. DE LOACH AND WILLIAM A. CATLETT, OF DALLAS, TEXAS.

GAS BURNER.

Application filed September 24, 1924. Serial No. 739,688.

To all whom it may concern:

Be it known that we, MITFORD B. DE LOACH and WILLIAM A. CATLETT, citizens of the United States, residing at Dallas, in the 5 county of Dallas and State of Texas, have invented certain new and useful Improvements in Gas Burners, of which the following is a specification.

This invention relates to new and useful 10 improvements in gas burners employed for industrial purposes.

The primary object of the invention is to provide a device of this character which will be simply constructed and easy to regulate 15 and adjust.

Another object of the invention is to provide a burner which will emit a short but intense flame at the front of a boiler and give maximum heat in a minimum of time, 20 thereby conserving fuel used.

A further object of the invention is that the burners may be adjusted and regulated simultaneously with the admittance of air in front of the grate and with the flow 25 of gas.

With the above and other objects in view, the invention will be more fully understood by reference to the following description, in connection with the accompanying drawings and wherein:

Figure 1 is a side elevation of the invention partly in section.

Figure 2 is a partial horizontal sectional and top view.

Figure 3 shows a detailed view of the operating or control lever.

Figure 4 is a detailed view of the door adjustment rod.

Continuing the description of the invention and referring to its various parts more 40 in detail, 1 represents the housing of the apparatus, to the forward end of which are welded or otherwise suitably secured members 2 which form a grate.

Each grate 2 has a lip 2^a for the burner when the latter is closed. Doors 3—3 are attached to the rear side of the housing for the purpose of admitting air into the housing and the doors will be hereinafter referred to. Plates 3^a—3^a are attached to the outside of the door and have perforations 20—20 therein. The doors are hinged at points 21 on upright inwardly extended guide members 19. Rods 4, slidable on members 4^a and adjustable by a set screw b, con-

nect the doors to a packing box 10 which is 60 slidable on a packing gland both packing box and gland 11 being slidably arranged on a gas supply pipe 12.

A gas chamber 6 is adapted to be moved 65 in guides 5—5, which form a part of the members 19 and has a threaded opening e. Pipes 7 with adjustable couplings 7^a are screwed into the front face of the gas chamber 6. These pipes have laterally arranged 70 burner heads 8 with openings a—a and the burner heads are arranged to conformally fit the openings in the grate. These burner head openings permit a flame of gas to be projected centrally through the apertures 75 in the grate, and it will be seen that the burner heads are slidable on members 18—18. A gas inlet pipe 9 is centrally secured in the side of the gas chamber opposite the burner pipes. The packing box 10 80 forms an integral part of this pipe and 9^a represents an air-tight connection of the pipe 9 to the gas chamber. The gland 11 is adapted to slide in the packing box and has a like attachment to the gas supply pipe 12. A valve 13 is provided for controlling 85 the gas flow and is placed in alignment with the pipe 12, the latter being connected to a gas main 17. A square valve stem 14 has a lever 15 which is bent to form an angle of forty-five degrees from the horizontal see 90 Figure 3. This lever has a plurality of apertures c—c in its end for adjustably attaching it to the lever 16. The lever 16 it will be noted extends from and is attached to the sleeve or stuffing box 10 and has 95 perforations f—f for making alteration at the point d.

Referring to Figure 1, in operation the invention has the lever 15 shown in position with the gas shut off, the burner heads being seated in the grate and the doors closed. As the lever is depressed, the valve stem 14 is turned to admit the gas and at the same time the doors 3—3 are opened and the burner heads are moved away from the grate. The supply of air through the doors and through the grate on each side of the burner and the supply of gas entering through the inlet pipe is thus controlled by a single lever. If the amount of air admitted through the doors is of too great a volume, the rods are moved in the apertures at points 20—20, until the correct amount of air in relation 100 to the influx of gas and the relation of the 105 110

burner heads to the grate is secured. If too much gas or too little is admitted, the adjustment at *c* is changed. On depression of the lever 15 past center, the gas chamber 5 and the burner head couplings are moved away from the grate, and the doors are pulled open and the valve operated to allow the entrance of gas to the chamber and to the burner heads.

10 When the apparatus is closed or temporarily inactive the lever 15 is raised to the position shown in Figure 1, a point just before it reaches center.

It should be understood that changes in 15 arrangement and construction of the invention may be made without departing from the spirit thereof and within the scope and meaning of the following claims:

1. An apparatus of the character de-
scribed comprising a housing with doors, 20 a grate, a plurality of burners of substantially T-shaped formation adapted to be moved to and away from said grate, a gas reservoir with a gas supply pipe, a second pipe with a valve and having air-tight connection with the gas supply pipe, and a lever for opening said valve and simultaneously moving said burners away from the grate, and opening the doors, said movement being reversed on operation of the 25 lever in an opposite direction.

2. A gas burner comprising a housing, a grate formed with the forward end thereof, said grate consisting of a plurality of laterally extending spaced lips having openings therein, a V-shaped burner head for each lip having a plurality of perforations adapted to register with the openings within said grate lips, a gas supply pipe leading 35 to the medial portion of each burner head at the side thereof opposite to the side containing said perforations, and guides arranged upon the opposite sides of said housing for said burners whereby the latter may 40 be moved to and from said grate.

3. A gas burner comprising a housing, a grate formed with the forward end thereof having a plurality of horizontally arranged openings therein, a vertically extending gas 50 reservoir slidably mounted within said casting, a plurality of longitudinally extending pipes leading from said reservoir, a burner head for each pipe adapted to be received by said horizontally extending openings 55 within said grate, a gas supply pipe leading to one side of said reservoir, a packing box for said gas supply pipe, a main gas pipe, a gland secured to said main gas pipe and received by said packing box, and means operatively connected to said packing box for 60 sliding the latter upon said gland, substantially as and for the purpose specified.

4. An apparatus of the character de-

scribed comprising a housing enclosing a plurality of burners, means for slidably supporting said burners, a gas reservoir, means for slidably supporting said reservoir, means connecting the burners with said reservoir, doors with adjustable means and hingedly connected to said reservoir supporting means, a pipe connected to said reservoir and having connection with a packing box the latter connected to a gas supply pipe, a valve in said supply pipe, and a lever; said apparatus adapted to be operated and controlled by the manipulation of the lever to open and close the gas supply valve, operate the doors and slide the burners and reservoir to and from the grates to admit air and gas in the operation thereof.

5. A gas burner comprising a casing having the rear end thereof opened, a grate formed with the forward end thereof, a plurality of burner heads slidably mounted within said casing and adapted to cooperate with said grate, a sectional gas supply pipe, one section having one end thereof extending within said casing and connected to said burner heads, a packing box formed with the opposite end thereof, a gland formed with the other section of said pipe and received by said packing box, a control valve arranged within said last mentioned section, a pair of hingedly supported doors for closing the rear open end of said casing, an apertured bar secured to the outer face of each door, and means for operatively connecting said apertured bars of said doors, packing box and valve, substantially as and for the purpose specified.

6. A gas burner comprising a housing, grates formed therewith, guides arranged within said housing and secured to the opposite walls thereof, burner heads slidably mounted within said guides and adapted to cooperate with said grates, a gas reservoir slidably mounted within said housing and having communication with said burner heads, hingedly mounted doors for closing openings leading within said housing, a gas supply pipe having a valve therein, a slideable connection between said reservoir and gas supply pipe including a packing box, an angular control lever connected to the valve of said supply pipe, a rod pivotally connected at one end to said packing box, an adjustable connection between the opposite end of said rod and said control lever, and adjustable connections between said packing box and doors.

In testimony whereof we have signed our names to this specification.

MITFORD B. DE LOACH.
WILLIAM A. CATLETT.
